[57] ABSTRACT

Game apparatus comprising a game board which is provided with squares numbered from 2 to 12, corresponding to the available numbers that can be rolled with a pair of dice; a pair of dice; a can-shaped member; spring means to project the latter; and 10 playing pieces. Basically, the game is played by the various participants rolling the dice and moving a number of positions on the board corresponding to the number rolled on the dice. The "protector of the can" who subsequently rolls the dice captures the playing pieces of those players, if any, who rolled the same number as he did. Any player who rolls 12 releases any captured players, who again become participants. This comprises "kicking the can" which is physically performed by the player who rolled 12 placing the can-shaped member upon the spring means, depressing same, and projecting the can into the air. The game ends upon capture of all playing pieces by the "protector of the can."

BOARD GAME APPARATUS

BACKGROUND OF THE INVENTION

This invention pertains to those arts concerned with amusement and educational devices.

The present invention provides a game which is not only very amusing as well as educational, but is also simple in construction and inexpensive to manufacture. It can be designed to allow numerous participants and which tests their dexterity, memory, and mathematical reasoning.

DESCRIPTION OF THE DRAWING

FIG. 1 in the drawing is a plan view of the playing board utilized in playing the present game.

FIG. 2 represents an isometric view of a typical playing piece which is used pursuant to playing the present game.

FIG. 3 is an isometric view of the can-shaped member which is figuratively "kicked by the player."

FIG. 4 is an isometric view of an ordinary pair of dice used to play the present game.

FIG. 5 is an isometric view of spring means employed in conjunction with the can member of FIG. 3.

SUMMARY

The instant invention provides a game apparatus comprising a playing board provided with a number of player columns which are divided into 10 individual playing positions numbered 2 to 11 consecutively and which extend from a number 1 position constituting a "SAFE ZONE" to a number 12 position constituting a "CAPTURE ZONE." The board is also provided with a zone entitled "KICK THE CAN" wherein a can-shaped member is positioned by a player for its projection into the air pursuant to playing the game as hereinafter defined. Resilient means are also provided for projecting the can-shaped member into the air. A pair of conventional dice and a number of individual playing pieces corresponding to the number of participants are additionally provided.

DESCRIPTION OF THE PREFERRED EMBODIMENT

Referring to FIG. 1 in the drawing, the playing board 10 is provided with a number of player columns corresponding to the number of participants desired to be allowed to play the game. These columns extend along one dimension of the board and preferably comprise about 10. The columns are divided into 10 individual playing positions or blocks which are numbered 2 through 11 consecutively. A number 1 position is provided wherein the player's pieces are initially positioned. This position is entitled SAFE ZONE and is designated by the reference numeral 11. The playing pieces move from this zone to the various playing positions 12 in the manner of playing the game as explained in detail hereinafter.

The board 10 is also provided with the zone 13 entitled CAPTURE ZONE which constitutes a number 12 playing position. The zone 13 is further subdivided into another area 14 which is entitled CAN wherein a resilient spring means is operably positioned. This area 14 constitutes the essence of the present game to the extent that the objective of a participant is to "kick the can," figuratively speaking, by reaching the number 12 position and "kicking the can" by placing the can-shaped member 15 of FIG. 3 onto the resilient means 16 and projecting it into the air. Correspondingly, the objective of the dealer or "protector of the can," is to capture all of the participants. The zone 13 is also designated as KICK THE CAN since a participant is allowed to do so upon attaining that position other than by being captured.

The board 10 is preferably provided with the recessed portions 17 wherein the various playing pieces are stored when not in use. The individual playing pieces 18, for example as shown in FIG. 2, are preferably designed or shaped to fit within these recessed portions. In the case of the embodiment of FIG. 1, 10 playing pieces would be provided such as that shown in FIG. 2. The base portion thereof would be shaped to

fit within its corresponding similar shaped recessed portion of the board 10, e.g., the member of FIG. 2 being round at its base, it would fit within the recess 20. The various playing pieces 18 are preferably colored different colors to match the corresponding colored playing columns of the board 10. Additionally, the playing board is preferably provided with the starting positions 21 which match the base portion and color of the respective playing pieces. The dealer or "protector of the can" does not employ a playing piece.

FIG. 5 of the drawing depicts a preferred form of resilient spring means 16 which is operably positioned in the zone entitled CAN. It is adapted to receive the can 15.

FIG. 4 depicts a pair of conventional dice which are employed to play the present game in the manner set forth hereinafter.

To start the game, all players should dice. The player who dices the lowest is the "protector of the can." The player who dices the highest chooses any "safe position" in the safe zone. The man he chooses to represent him must be placed in the row of the same color and having a recess of a shape corresponding to the shape of the base of the man chosen. The remaining players then choose their men and they also must abide by the rule of placing their men in the row corresponding to the color and base shape of their man. Once all players have been placed in their safe position, the game starts with the player who dices the highest dicing first. Moving from left to right, the next player takes his turn and so on until all players have had a first turn. The "protector of the can" must always dice after all players have diced.

The key number is "12." This number when diced only after all players have had their first dice allows the player to "kick the can." If a player dices "12" on his first dice he is permitted to stay in the safe zone until his second turn to dice comes up. If he dices "12" on his second turn, which is after all other players, including the "protector of the can," have had their first dice, he is then allowed to "kick the can." If he does not dice "12" on his second dice then he must move out of the safe zone to the number which he has diced.

Players who have not diced "12" on their first dice must move out of the safe zone to the number corresponding to the sum of the dice. For example, a player is in the safe zone, he dices and the number is a number other than "12," then he must move directly to that number. If that number is "7" then he must move down to that number. He is now subject to capture by the "protector of the can."

Once all players have diced, the "protector of the can" then dices. All players who are on the number corresponding to the number diced by the "protector of the can" are captured and are placed in the capture zone on the bottom of the board. Those players in the capture zone must remain there until a player dices "12" which allows that player to "kick the can." When the can is kicked all captured players are freed.

Players who are not captured after their first dice then dice a second time. A player who dices a number higher than the number which he is on must move to that number. For example, a player is on number "2" and he now dices "8," then he must now move to number 8. If a player dices a number lower than the number which he is on he is permitted the choice of remaining on that number or moving back to the lower number. Before a player moves back to a lower number he should decide which number offers him the safest position. By safe position is meant a position as close as possible to the number 2 or 11 since the probability of the protector of the can dicing these numbers is less. In other words, based upon probability when rolling a pair of dice, there are more combinations of numbers that can be diced to achieve the number 7. As you recede from the number 7 in either direction, that is, toward number 2 and number 11, respectively, the probability factor becomes greater. For example, number 2 can only be diced one way, that is, by dicing number 1 on each die, whereas, in the case of number 11, it can be diced two ways, that is, by dicing 5 or 6 on one die and 6 or 5 on the other, respectively. Accordingly number 2 thereby represents the safest position on the board and number 11 the second safest.

A player who dices the same number which he is on is allowed to return to the safe zone where he is given three consecutive turns to dice. If he does not dice "12" on his third dice he must again move out to the number corresponding to the sum of his last dice. If he should dice "12" during his three chances he is permitted to "kick the can."

Any player who dices "12" any time after his first dice can approach the can and "kick" it. When the can is "kicked" by any player all captured men are freed. All men then must immediately return to their original position in the safe zone. This must be done before the "protector of the can" can place the can back into its original position. Any player who has not returned to his starting position by the time the can is placed back into its position is captured and placed in the captured zone. The person who is the "protector of the can" remains the same until all players are captured. Only when all players are captured is the "protector of the can" allowed to change position.

The player who was captured first then becomes the new protector of the can. The last protector of the can is then given the option of position in the safe zone. He then starts the game by dicing first.

The present game can be constructed of any appropriate material of construction, e.g., the board can be made of cardboard, plastic, etc., and constructed either in a solid piece or in sections to be folded.

5 What I claim is new is:

1. Game apparatus comprising a playing board having defined thereon a plurality of player columns, each divided into 10 individual playing positions consecutively numbered 2 to 11, an area of said board above said columns being labeled 10 Safe Zone, and an area of said board below said columns being numbered 12 and labeled Capture Zone; a number of playing pieces equal to the number of player columns; a pair of conventional dice, each die having its faces marked with indicia representing the numbers 1 to 6, respectively;

15 said playing board being further provided with a zone labeled CAN,

resilient means operably positioned within the zone on said board designated CAN; and

a can-shaped game piece adapted to mate with said resilient means for positioning thereon and projection thereby when released.
